ATTORNEYS.

UNITED STATES PATENT OFFICE.

ALBERT P. DAVIS, OF BINGHAMTON, NEW YORK.

PHOTOGRAPHIC-FILM HOLDER.

Application filed May 21, 1924. Serial No. 714,815.

To all whom it may concern:

Be it known that I, ALBERT P. DAVIS, a citizen of the United States, residing at Binghamton, in the county of Broome and 5 State of New York, have invented certain new and useful Improvements in Photographic-Film Holders, of which the following is a specification.

My invention relates to improvement in 10 apparatus for developing, fixing, and washing photographic films. Its purpose is to enable more holders to be hung in the bath tank in a given space than now possible, increase the capacity of the bath tank, 15 simplify the holding parts of the apparatus and manufacture of the same, eliminating the use of screws, slots and solder, and to cause the surface of the films to be uniformly separated, regardless of the position 20 of the holder, and to permit of easy positive adjustment of the film support to varying thickness of the base bar, due to shrinkage and swelling of the same, and to eliminate the multiple or bifurcated base board, a 25 part of my device under my former patent, dated March 2d 1915, No. 1,130,152.

With these objects in view my invention consists of certain novel features of construction and arrangement of parts, as will 30 be hereinafter more particularly described and pointed out in the claims; reference being had to the accompanying drawings, in which—

Fig. 1, is a perspective view of my device, 35 and new form of film holder.

Fig. 2 shows my new film holder in place in a developing tank.

Fig. 3 is an end view of my device.

Fig. 4 is a perspective view of a film holding device.

The same reference characters denote like parts in each of the several figures of the drawings.

In carrying out my invention, I provide 45 a support bar A, on which is slidably mounted or brought into position, the fixing supports B and B', one of which B, is held in fixed position and the other is adjustable and movable. These supports B and B' are 50 formed of a single piece of wire bent so as to form the two projecting arms V shaped, a and b and a' and b' so as to form the connectors 2, 2 and 2', 2' for connecting the supports B and B' to the bar A. The formation 55 of the film supports holds the film in place, while reducing the amount of metal

in actual contact with the film, also prevents the film from coming in contact with the sides of the tank, by holding it in diagonal alinement with the support bar, and maintaining complete uniform separation between the film sides. Between the connectors 2, 2 and 2', 2', I have mounted the plate d, the ends of which are bent around the connectors 2, 2 and 2', 2' or joined in 60 any other convenient method. As a further feature of my device, in the supports B and B', I have the arms a and a' crimped at E.

The supports B and B' are mounted to 65 position by sliding them along the bar A and may be disengaged from the bar A, and the distance between the two supports B and B' may be varied at will, not only for the purpose of stretching the film taut, but also for adjustment for different lengths 70 of film. The fit of the base or support connectors 2', 2' on the bar A are such that the supports may be very slightly tiltable towards the support B or may be held in close adjustment for a purpose hereinafter 75 explained. The support B after being moved along the bar or support A to its position, can be brought into close engagement, and held stationary, by inverting the support A and bending the ends x, x of the 80 connectors 2, 2 into close contact with the surface of A. Also by bending the bent ends x, x towards each other, the space filled by the base bar or support is narrowed 85 or lessened and by bending from each other 90 said space is increased. By this means perfect contact with the base bar or support is maintained, under all atmospheric conditions and any shrinking or swelling of the base bar or support is compensated for. 95 The support B' is left in slidable and adjustable position along the bar A. I have found that when the ordinary film is slightly wetted at its ends, while the latter lie in overlapping contact with one another, 100 and are held pressed together, the ends will adhere firmly, so that the film will retain after immersion the form of a closed band, which permits the finished film to be handled with very little trouble, or they 105 may be pinned together. In order to bring suitable pressure upon the overlapping ends, I may provide a U shaped clasp or clip 4, which clip is resilient and may fit snugly upon the supports at E, and in this way 110 bring suitable pressure upon the overlapping ends 5 of the film. As shown in Fig.

2 these ends are interposed between the arm *a* of support *B* and the inner face of the clip 4, or they may be pinned together. In using my improved film holder, the film 5 *C* is bent around the arms *a*, *a'* of the supports *B* and *B'* in the manner shown in Fig. 1 and Fig. 2, and the overlapping ends 5 are engaged and held by the clip 4 or they 10 may be pinned together. The film *C* is then stretched taut by sliding the movable support *B'* along the support or bar *A*, the support *B* being held stationary as above described. When the film *C* is sufficiently stretched, it will be found that the film 15 *C* has tilted slightly the support *B'* so that the arm *a'* and connector 2 binds upon the bar or support *A*, and in this manner the support *B'* is automatically secured firmly in place. The inner sides of the film *C* 20 rest upon the crimp points at *E*, and are held apart from contacting with each other. The film holder is then inverted and placed in the developing tank *D*, in the developing solution contained therein, the ends of bar 25 or film holder *A* resting upon the edge or rim portion of the tank *D*. Between the film ends which are held pressed by the clip 4 or pinned together and against the arm *a* of support *B*, and at the crimped section 30 *E* the solution enters in such amount as to wet the film ends slightly and the latter will be found to adhere firmly to each other. The film is immersed edgewise in the developing solution, causing every part of 35 every film to be acted on uniformly and equally throughout the whole extent of its surface, and any sediment or other foreign matter drops to the bottom of the tank. After sufficient development, the bar *A* is 40 raised from off the tank *D* and the film immersed in the fixing bath. From the fixing bath the film holder is moved to the washing tank for thorough cleansing. By the use of my new film holder, and by mounting 45 the films upon the supports *B*, *B'* with the resultant absence of marring or tarnishing, an improved quality of product results, the staining of the operator from the solution is avoided, the films subjected to even 50 treatment, and are ready for printing.

By my new form of film holder, an increased number of films may be mounted in the tank, and treated in the shortest time, and passed to another operation. At the same 55 time, the use of this film holder shortens the time of the operator in the dark room. By

the use of this film holder, the operator can immerse more film holders at one time in the immersion tank, a greater number than by the use of other forms of holder, and increase the capacity of the tank mentioned above, 50%, at the same time obtaining uniform action by the solution, to which they are subjected. While requiring less room in the use of the film, yet it produces a 60 larger yield of finished perfect films. The device is durable and inexpensive in manufacture, and with little cost of upkeep and for repairs. The advantages of this new 65 form of film holder, over the film holder described in my patent, dated March 2, 1915, No. 1,130,152 are obvious.

Thus having described my invention, what I claim as new and for which I desire Letters Patent is as follows:

1. In a photographic film holder, comprising a base bar, a pair of film holding supports, mounted by sliding along the base bar, to any desired distance, the supports formed of one piece of wire, bent into two V shaped projecting arms, one of the arms of each support crimped in alinement, the ends of the arms bent over the rectangular base bar, the bends conforming to the side surfaces of the bar, and forming slidable connection therewith, a tie strap mounted between the bended ends, along one face of the bar, means for automatically locking the supports, at any given point along the base bar.

2. In a photographic film holder comprising a rectangular base bar, slidably mounted on the same a pair of film holding supports, said supports formed of one piece of wire, bent at the middle and branching in V shaped formation, one of the branches crimped in outline, the ends of the branches bent around the sides of the bar, the bends in alinement with the sides, a strap mounted along one face of said bar, connecting the bends in said arms, the arms of one support mounted in alinement with one side of said bar, and the arms of the other support in alinement with the other side of said bar, the bent ends of one support crimped into the under surface of the bar, holding it in fixed position, the other support slideable upon the bar.

In testimony whereof I have affixed my signature.

ALBERT P. DAVIS.
